APPARATUS FOR THE MANUFACTURE OF ENRICHED WATER GAS AND COAL GAS

Filed April 3, 1929

UNITED STATES PATENT OFFICE

ALBERT VICTOR TULLY, OF NEWARK-ON-THE-TRENT, ENGLAND

APPARATUS FOR THE MANUFACTURE OF ENRICHED WATER GAS AND COAL GAS

Application filed April 3, 1929, Serial No. 352,217, and in Great Britain April 4, 1928. CR

In the manufacture of gas by alternately blowing fuel to incandescence with air and then passing steam through the mass of the fuel, the said blowing step causes part of the fuel to be blown out of the stack valve in the form of breeze and dust. To prevent the loss thus represented and overcome the objection thereto which obtains in populous districts, a cyclone separator is sometimes fitted 10 to receive the discharge past the stack valve. Furthermore provision is in certain plants made for recovery of heat of the air blow gases by means of a chamber between the generator and the stack valve, in which chamber 15 dust is trapped.

The object of the present invention is to effect an improvement in the apparatus whereby the fuel particles from the air blast gases are more effectively arrested and separated 20 before the stack valve is reached with at the same time recovery of sensible heat available for the superheating of steam in a down run following an up run or for fixing vapor for enrichment of the water gas made by means 25 by the injection of oil or other suitable hydrocarbon during a gas making period.

With this end in view the invention consists in combining with a gas generator a cyclone dust extractor, the outlet of which 30 is connected to the stack valve, while in addition there is a connection adapted to enable steam to be passed through the dust extractor into the gas generator. A further connection may be provided for allowing gas 35 to pass from the generator through the dust extractor with the stack valve closed.

In the accompanying drawing whereof Fig. 1 is a sectional elevation and Fig. 2 a part 40 sectional plan, there is shown as employed a water gas generator 1 of a well known type embodying a superposed coal distillation retort 2, coal being fed through a charging door 3 at the top and descending by gravity through the retort to the generator. Checker work 4 surrounds the retort. During the

blowing period air is admitted by way of the valve 5, beneath the grate 6 of the water gas generator, passes up through the carbonized fuel in the said generator, leaves the fuel bed by nostrils 7 and enters a combustion 50 chamber 8 beneath the checker work 4 where a further supply of air is admitted by a valve 9, causing combustion of the whole or a portion of the carbon monoxide content of the air 55 blast gases. The products of this combustion pass up through the checker work surrounding the superposed retort 2, finally leaving as by a branch piece 10 which enters tangentially a vessel 11 in such manner as to separate the dust particles in the known manner 60 of a cyclone extractor. Owing to the speed at which the burned blast gases pass around the vessel 11 the particles are projected by centrifugal force and gravity outward and downward towards the outer surface, finally 65 descending into a collecting pipe 12. The gases free from dust and fuel particles, pass through openings 13 in the wall of a central flue 14 which has its bottom end closed, as indicated at 26, and at its top end communicates with the atmosphere through the stack pipe 15 and valve 16.

During the passage of the burned blast gases through the vessel 11 a portion of the sensible heat is given up to the brickwork 75 forming the lining 17 and central flue 14 of such vessel.

With such apparatus, water gas is made by admitting steam either below the grate 6 as through the inlet 18 for the up run or 80 into the dust extracting vessel 11 near the bottom as through the inlet 19 for the down run. In the former case the steam passes up through the incandescent fuel bed in forming water gas, which water gas passes up 85 through the coal in the retort 2 and with an admixture of coal gas leaves by a gas outlet 20 connected to a valved seal-box which is not shown. In the second case the steam entering the vessel 11 passes up through the 90

vessel, in which it is superheated by taking up heat from the brickwork forming the lining 17 and flue 14 of such vessel. It then passes through the branch or like connecting member 10 referred to and downwards through the checker work 4 and carbonized fuel, forming water gas which leaves by a gas outlet 21 below the grate 6 also communicating with the valved seal-box.

10 When it is desired to enrich with oil or other hydrocarbon the gas produced, oil is admitted at a convenient position as for example through the inlet marked 22 to the checker work 4 where such oil or other hydrocarbon is cracked to an enriching oil vapor. In such case, only a part of the water gas produced in the generator by the admission of steam below the grate is allowed to pass up through the retort and away by the associated gas outlet 20 to the valved seal-box the remainder of the water gas produced being caused to pass up through the checker work and so carry forward to the dust extracting vessel the oil vapors produced by the admission of oil. The dust extracting vessel 11 in this case serves as a fixing chamber for the oil vapors, and the oil enriched water gas leaves this vessel by a gas outlet 23 adjacent to the stack valve and also connected with the valved seal-box, where it is mixed with the uncarburetted gas simultaneously leaving the generator by the gas outlet 20 near the top of the retort.

15 The solid material collected in the dust extracting vessel 11 is periodically discharged through a duct 24 by the opening of a valve 25.

20 What I claim is:—

1. An apparatus for producing enriched water gas and coal gas having in combination: a water gas generator having air and steam inlets, a superposed coal distillation retort, a checkerbrick chamber surrounding the distillation retort, a gas outlet pipe connected to the top of the retort, an oil inlet connected to the checkerbrick chamber, a separate combined dust separating and oil fixing chamber connected to the checkerbrick chamber, a central flue having a perforated wall in the dust separating and fixing chamber, an inner heat retaining lining in the dust separating and fixing chamber and a steam inlet to the dust separating and fixing chamber.

2. An apparatus for producing enriched water gas and coal gas having in combination: a water gas generator having air and steam inlets, a superposed coal distillation retort, a checkerbrick chamber surrounding the distillation retort, a gas outlet pipe connected to the top of the retort, an oil inlet connected to the checkerbrick chamber, a separate cylindrical combined dust separating and oil fixing chamber, a duct connecting the checkerbrick chamber to the dust sepa-

rating and fixing chamber and entering the latter tangentially, a central flue in said dust separating and fixing chamber, said flue having a perforated wall and a closed bottom end, an inner heat retaining lining in the dust separating and fixing chamber and a steam inlet to said dust separating and fixing chamber.

Signed at Nottingham, England, this 16th day of March, 1929.

ALBERT VICTOR TULLY.
